CLAIM

The ornamental design for an intake manifold, as shown.

DESCRIPTION

FIG. 1 is a perspective view of an intake manifold according to our new design;

FIG. 2 is a top plan view of the intake manifold of FIG. 1; FIG. 3 is a bottom plan view of the intake manifold of FIG. 1

FIG. 4 is a front elevational view of the intake manifold of FIG. 1;

FIG. 5 is a rear elevational view of the intake manifold of FIG. 1;

FIG. 6 is a left side elevational view of the intake manifold of FIG. 1;

FIG. 7 is a right side elevational view of the intake manifold of FIG. 1;

FIG. 8 is a perspective view of an alternate embodiment of an intake manifold according to our new design;

FIG. 9 is a top plan view of the intake manifold of FIG. 8; FIG. 10 is a bottom plan view of the intake manifold of FIG. 8;

FIG. 11 is a front elevational view of the intake manifold of FIG. 8;

FIG. 12 is a rear elevational view of the intake manifold of FIG. 8;

FIG. 13 is a left side elevational view of the intake manifold of FIG. 8; and,

(Continued)

FIG. 14 is a right side elevational view of the intake manifold of FIG. 8.

The broken lines corresponding to the interior surface of the intake manifold depict a portion of the intake manifold forming no part of the claimed design.
